BARREL CONSTRUCTION

Stevens A. Bennett, Chicago, Ill., assignor to
 Wilson & Bennett Manufacturing Company,
 Chicago, Ill.

Application March 5, 1929. Serial No. 344,476

5 Claims. (Cl. 220—59)

This application is a continuation in part of my former applications for Barrels or drums Serial No. 118,430 and Barrels Serial No. 187,864, insofar as common subject matter or invention is 5 involved.

This invention relates to relatively large-sized containers such as are ordinarily known as barrels or drums as distinguished from smaller sized containers known as cans or pails. Steel barrels of this character are usually made of relatively heavy sheet steel with the heads double seamed or otherwise securely fastened to the bodies. The desirability of having such heads provided with relatively large openings has long 10 been recognized, but no satisfactory closures have been provided for such openings. While an ordinary bung is satisfactory for shipping various liquids no satisfactory means has heretofore been provided for fastening covers to barrel heads for 15 closing large openings. When nuts or bolts are used for this purpose, it has been found difficult to properly fasten the cover, and the nuts or bolts are apt to become lost or injured so that the cover cannot be readily replaced. The forming 20 of the heads of such barrels of heavy sheet metal has undoubtedly prevented attempts to fashion the same for otherwise securing covers thereto.

In accordance with the present invention, I 20 provide a barrel or drum which may be made of relatively heavy sheet steel, say of approximately eighteen gauge for the larger sizes and twenty-two gauge for the smaller sizes, with a large opening in the head and a cover for such opening 25 which may be applied by means of a cover closing or crimping machine such barrels being adapted for holding and shipping heavy materials such as paints, oils, greases, red lead and the like, weighing up to twelve hundred pounds for a 30 sixty-five gallon barrel.

The objects of this invention are to provide a barrel or drum with a head having a large opening therein and a novel cover which is adapted to be secured directly to the head without 35 other fastening devices; to provide a barrel having a head with a neck formed therein for receiving a cover, said neck projecting outwardly a sufficient distance to permit the application of a cover closing machine for fastening a cover in 40 position; to provide a barrel having a head which is depressed or set in and having a neck outlining a relatively large opening, say of eleven or 45 twelve inches, said neck having an outwardly projecting flange, and a cover which is adapted to 50 engage with the neck and to be securely fastened

in position by a suitable closing machine, and such other objects and advantages as will be described hereinafter.

In the accompanying drawing illustrating this 60 invention,

Figure 1 is a side elevation of the upper portion of a barrel with parts broken away or shown in section and a portion of a cover closing machine shown in position for the closing operation;

Figure 2 is an enlarged detail sectional view of a portion of the neck and cover before the closing is effected; and

Figure 3 is a similar view showing the cover in closed or crimped position.

As shown in the drawing, the barrel or body 4 has a head 5 which is secured thereto in any suitable manner as by means of the double seam 6. The head is preferably provided with a flange 7 whereby the main portion is offset depressed or let in in the usual manner. A part of the head, as indicated at 8, is further offset depressed or let in to provide space between the same and the end of the barrel. A neck or cylindrical projection 9 extends upwardly from the depressed portion 8 and has a relatively large opening therein. The outer portion of the neck has a flange 10 which may be of any desired form but which is preferably curved or curled and which extends outwardly a sufficient distance to receive the cover closing means. When the metal is too heavy for it to be practicable to form a bead for receiving the cover, such flange has been found sufficiently stiff and rigid to properly hold the cover in position. Such curved flange makes a desirable periphery for the opening as a man may reach his arm in without danger of injury from sharp edges.

The cover 11 has a central or main portion 12 with an annular flange or cylindrical portion 13 which fits within the neck 9. The flange 13 has an outwardly projecting curved rim 14 which conforms in general to the flange 10 and is adapted to fit closely thereover. The cover is provided with a plurality of closing tabs or lugs 15 which are adapted to be bent or crimped inwardly up in under the flange 10 for holding the cover in position. These lugs are bent outwardly to provide projections 16 at their lower ends and are preferably provided with slots 17 which are adapted to be engaged by a suitable tool for removing the cover.

When the cover is to be applied, it is placed in position, as shown in Figure 1, preferably with a gasket 18 interposed between the flange 10 and coacting flange or rim 14. A can closing ma-

- chine such as indicated at 19 is then applied to the cover with its closing jaws 20 positioned to engage the lugs or tabs 15, as shown in Figure 1. The neck 9 extends outwardly from the cover far enough and is spaced from the rim or edge of the barrel a sufficient distance to permit the proper manipulation of the closing jaws or levers 20 in order to perform the closing movement. When the cover is closed, the gasket 18 is compressed and the lugs or tabs 15 are bent inwardly under the flange 10 with portions thereof pressed against the sides of the neck, as shown in Figure 3 and with the lower ends 16 bent outwardly at acute angles to the neck in the manner shown.
- 15 During this closing movement the jaws press inwardly and downwardly on the ends 16 to cause them to be partially straightened and at the same time to force the intermediate portions against the neck. Any suitable number of these lugs or projections may be provided, but I have found that sixteen is sufficient for most purposes, and when these lugs are bent under the stiff flange 10 with the parts thereof braced against the sides of the neck 9, the holding portions of the
- 20 cover are stiffened and the cover will be held securely in position for all the usual commercial purposes. It will also be noted that the head is offset or let in sufficiently so that the cover does not project beyond the rim or end of the barrel.
- 25 30 The convenience and speed with which the closures may be made are advantages of utmost importance.

It will be noted that the ends 16 of the lugs are bent outwardly a sufficient distance so that the lower edges of the slots 17 are free from the neck, which permits the easy insertion of a screw driver or other tool through the slots to bend out the lugs when the cover is to be removed. The lugs may be bent outwardly to approximately 40 their original position, and the cover may then be used again or may be merely pushed into position for ordinary closing purposes.

Having thus described my invention, what I claim and desire to secure by Letters Patent is:

45 1. A sheet steel barrel construction, for barrels formed of heavy gauge sheet steel and adapted for shipment of heavy contents weighing in the hundreds of pounds, comprising a body having a head set in from the end thereof, said head having an outwardly projecting integrally formed neck of large diameter which terminates below the end of the barrel and having an annular flange 50 around the end thereof, a cover coacting with the neck to close the opening therethrough, and 55 means associated with the cover and adapted to

be acted upon by a closing machine for securing the cover to the neck.

2. A container of the character set forth formed of heavy gauge sheet steel and adapted for shipping heavy materials weighing in the hundreds of pounds having a head with a neck projecting therefrom which terminates at approximately the top of the barrel with an outwardly extending flange at the end thereof, a cover fitting over the flange and provided with fastening means normally out of fastening position when the cover is first applied but which are bent in toward the neck and under the flange to fasten the cover in closed position.

3. A new article of manufacture comprising a heavy gauge steel barrel adapted for shipping contents weighing in the hundreds of pounds and having a head rigidly secured thereto, said head being provided with an integrally formed outwardly projecting neck having a flange at the outer end thereof, a closure for said neck having portions adapted to be bent under said flange to fasten the closure in position, the head and neck being sufficiently strong and suitably formed so that the closure may be applied and fastened by means of a cover closing machine having jaws for bending the portions of the closure under the flange said head being set in around the neck a sufficient distance so that the neck with the closure thereon will not project beyond the end of the barrel.

4. A sheet metal barrel comprising a body with a head secured thereto, said head having a projecting neck of relatively large diameter with a projection around the outer end thereof; a cover 110 adapted to engage with the neck and means for securing the same to the projection on the neck, said neck being of sufficient length and positioned to permit the application of a closing machine to the cover to fasten the same to the neck.

5. A heavy steel barrel having a head with a depressed portion and an upstanding collar bounding an aperture in the depressed portion of considerable less diameter than the head, the collar terminating in an outwardly extending annular flange which is adapted to support a closure for the aperture, said flange further providing on its underside, an abutment for coacting with closure clamp fastening means; a closure for said aperture having fastening means, sufficient space being provided between the flange and the head to allow the application of apparatus for contracting the fastening means.
